UNITED STATES PATENT OFFICE

2,523,041

SCREW DRIVER

Hugh H. McKenzie, Norfolk, Va.

Application March 3, 1948, Serial No. 12,789

9 Claims. (Cl. 145—65)

1

The present invention relates to a manually actuated tool of the type adapted to be rotated for turning a screw, nut or the like and the invention more specifically pertains to the structural features of the shaft and handle of such tools whereby a lever or wrench may be employed in association with the device to increase the torque that may be manually applied to the tool shaft.

It is an object of the invention to provide a tool such as a screwdriver with a lever or wrench receiving portion whereby a mechanical advantage is obtained for turning the shaft or blade with the handle serving as a bearing for steady-
ing the upper end of the shaft during rotation thereof by lever action.

Another object of the invention is to provide a screwdriver or similar tool with a handle having a cylindrical socket therein for receiving the end portion of the shaft provided with a portion which may be engaged by a wrench for rotating the shaft with the handle serving as a bearing journalling the shaft during rotation by the wrench including means whereby the shaft may be detachably locked to the handle permitting use of the tool as a conventional screwdriver.

Other objects and features of the invention will be more apparent as the present disclosure proceeds and upon consideration of the following detailed description and the accompanying drawing wherein an exemplary embodiment of the invention is disclosed.

In the drawing:

Fig. 1 is a side elevational view of a screwdriver exhibiting the invention with a portion of the handle shown in section.

Fig. 2 is a plan view of the upper end of the tool shaft illustrating the manner in which a ratchet wrench may be applied thereto.

Fig. 3 is a side elevational view of the tool shaft.

Fig. 4 is a longitudinal sectional view of a sleeve that may be employed within the handle.

Fig. 5 is an end view of the sleeve showing the shape of the mouth.

The present invention is directed to a tool wherein a ratchet wrench or other suitable lever may be arranged in engaged relation with the tool shaft so that more force may be applied for turning the shaft. The invention is particularly applicable to screwdrivers but the features thereof may be incorporated in other tools such as socket wrenches, tap wrench or any

manually operated tool provided with a handle and an elongated stem or shaft which is rotated for turning nuts, bolts, screws or the like. The embodiment shown in the drawing pertains to a screwdriver but it will be apparent that the blade portion or the lower end of the shaft 10 may be replaced with a socket for engaging nuts, bolts, or the like. The shaft at the upper end thereof is designed for cooperation with a handle which in one instance, serves as a bearing journalling the shaft for rotation and the handle may also be locked to the shaft whereby the tool may be used like a conventional screwdriver.

Referring to the drawing, there is shown at 11 a handle for the tool. This handle may be formed of wood or plastic and in such case a metal sleeve 12 may be arranged within the handle as shown in Fig. 1. The sleeve 12 is formed of any suitable metal and if the handle 11 is formed of plastic, this material may be molded around the sleeve 12. The sleeve 12 has flat faces 14 on the exterior and the lower portion thereof to prevent relative rotation of the handle shell relative to the sleeve 12. If desirable, additional or other means may be provided for preventing rotation of the handle shell relative to the sleeve 12. The assembly may also be provided with means for preventing the sleeve from being removed longitudinally of the handle shell. If the handle is formed of metal, the sleeve 12 may be omitted and the shaft-receiving socket hereinafter further described, may be formed in the metal handle.

In the embodiment shown in the drawing, the sleeve 12 is provided with a cylindrical shaped bore or opening 16 for receiving the upper end portion 17 of the shaft 10. This portion 17 of the tool shaft is cylindrical shaped and is adapted to fit snugly in the opening 16 but is free for rotation therein and the fit is such that the portion 17 may be readily moved longitudinally of the handle. The diameter of the socket portion 16 is accordingly only slightly larger than the shaft portion 17. The sleeve 12 is provided with a larger bore 18 which may be cylindrical or other shape, as long as the cross section of this part of the opening is large enough to accommodate a wrench or lever engaging portion 19 on the stem or shaft 10. In a preferred form, the enlarged opening 18 is cylindrical shaped and of larger diameter than the greatest cross sectional dimension of the shaft portion 19. The length of the enlarged bore 18 is substantially equal to the axial length of the

polygonal shaped wrench engaging portion 19 of the tool shaft.

In carrying out the invention, the mouth of the opening in the handle is so shaped as to cooperate with a suitable structure on the tool shaft to provide for keying or otherwise preventing relative rotation of the handle on the shaft. Such keying means may take numerous forms and in the example shown in the drawing, comprises a portion 20 on the tool shaft which is larger in overall cross section than the wrench receiving portion 19. The portion 20 may be of any flat face shape to fit within a similar shaped recess 21 in the mouth of the handle or sleeve 12. In the arrangement depicted in the drawing, the portion 20 and the recess 21 are polygonal shaped and each may be hexagonal in cross section. It will be understood that other cross sectional shapes may be employed for the walls of the recess 21 and for the flat faces of the enlarged portion 20.

The portion 19 is provided for the purpose of applying lever action to the shaft 10. Accordingly, this portion may be formed to have two or more flat faces and in the embodiment shown in the drawing, this part of the shaft is square in cross section for receiving a conventional type ratchet wrench 25 as shown in phantom lines in Figs. 1 and 2. The ratchet wrench may be of the reversible type so that it is unnecessary to remove the wrench for applying force in either direction of rotation of the shaft 10. It is to be noted that other wrenches or lever arms may be employed in association with the tool shaft and the portion 19 may be so shaped as to be operatively engaged by such levers or wrenches.

In use of the device, the tool shaft 10 may be detached from the handle 11 and the upper end 17 may then be introduced through the aperture in the ratchet wrench 25. The customary square hole in the rotor of the ratchet wrench is then fitted over the square portion 19 of the tool shaft. Thereafter the upper end portion 17 of the shaft is inserted in the socket 16 of the handle and moved upwardly therein to the position shown in Fig. 1. The upper end of the square portion 19 then extends into the recess 21 but there is no keying of the shaft 10 to the handle or sleeve 12 since the cross section of the recess 21 is large enough to permit the portion 19 to turn therein. This arrangement, however, prevents the ratchet wrench 25 from becoming disengaged from the lever arm receiving portion 19 of the tool shaft. The arm of the wrench 25 may then be employed to add power for rotating the tool shaft 10. The cylindrical shaft portion 17 is free to turn in the sleeve 12 and the cylindrical wall of the opening 16 serves as a bearing for the shaft. The handle 11 may then be employed to steady the upper end of the tool during use of the lever arm of the ratchet wrench for rotating the tool shaft.

Another feature of the invention pertains to releasably retaining the upper end 17 of the shaft within the handle while the wrench 25 is applied to the portion 19. This retaining means is designed to prevent unintentional separation of the tool stem from the handle and at the same time permit free rotation of the shaft within the handle 11. One type of such retaining means includes an annular groove 22 formed in the wall of the opening 16. A spring actuated ball 23 is carried by the upper end of the shaft as shown in Fig. 3. This ball may be depressed against the action of a spring (not shown) and the ball 23

is in a conventional manner retained in operative association with the cylindrical part 17 of the shaft ad its actuating spring. The groove 22 is so positioned longitudinally of the device that the ball 23 enters this annular depression when the parts are in the position shown in Fig. 1. The upper end 17 of the tool shaft is then free to turn in the socket opening of the handle but the ball 23 prevents unintentional escape of the cylindrical portion 17 from the socket opening and the handle.

If it is desired to use the tool as a conventional screw-driver, the shaft is withdrawn from the handle. The ball 23 is then depressed and rides on the wall of the opening 16 as the shaft is pulled from the handle. The socket wrench 25 is removed from the square portion 19 and from the upper end of the stem. The cylindrical portion 17 of the shaft is then reintroduced into the socket in the handle. The square portion 19 enters the enlarged bore 18 and the flat faces of the hexagonal portion 20 are introduced into the hexagonal shaped recess 21. The shaft 10 is thereby keyed to the handle and manual rotation of the hand grip will turn the shaft 10. The tool may then be used like a conventional screwdriver.

In order to releasably retain the parts in this assembled relationship, a further annular groove 24 is arranged in the wall of the opening 16. This annular groove is so positioned lengthwise of the handle that the ball 23 will enter the depression 24 when the end 26 of the hexagonal portion 20 engages the shoulder 27 forming the upper end of the recess 21. The tool shaft is thereby releasably retained in a position where the flat faces of the keying portion 20 will engage the flat walls of the recess 21.

While the invention has been described with reference to a screwdriver, other types of tools may be substituted for the blade shaped lower end of the shaft 10. Such changes and modifications in the shape of the interengaging parts and the materials employed may be made without departing from the spirit and scope of the invention as set forth in the appended claims.

What I claim and desire to secure by Letters Patent is:

1. In a tool, a handle having a cylindrical shaped opening therein, a tool shaft having a cylindrical shaped end portion extending into said opening, said handle having a recess at the mouth of the opening and of larger cross section than said cylindrical opening, at least one flat surface forming a wall of said recess, a flat surface carried by said tool shaft for engaging the flat surface of said recess to prevent rotation of the tool shaft relative to said handle; said handle having an annular groove within said cylindrical opening arranged in a plane at right angles to the axis of the cylindrical opening, a detent carried by the periphery of the cylindrical shaped portion of the shaft adapted to enter any portion of said annular groove when the flat surface on the tool shaft is positioned within said recess; and said detent being retractable into said cylindrical shaped portion of the shaft.

2. In a tool, a handle having a cylindrical shaped opening therein, a tool shaft having a cylindrical shaped end portion extending into said opening, said handle having a recess at the mouth of the opening and of larger cross section than said cylindrical opening, at least one flat surface forming a wall of said recess, a flat surface carried by said tool shaft for engaging the flat surface of said recess to prevent rotation of

the tool shaft relative to said handle, means releasably retaining the tool shaft within said opening with the flat surface thereof within said recess including a detent member releasably projected from the periphery of the cylindrical shaped end portion of the shaft and an annular groove within the cylindrical shaped opening for receiving the detent member.

3. In a tool, a handle having a cylindrical shaped opening therein, a tool shaft having a cylindrical shaped end portion extending into said opening, said handle having a recess at the mouth of the opening and of larger cross section than said cylindrical opening, at least one flat surface forming a wall of said recess, a flat surface carried by said tool shaft for engaging the flat surface of said recess to prevent rotation of the tool shaft relative to said handle, said cylindrical opening having an annular groove in the wall thereof, a releasable detent carried by said cylindrical shaped end portion of the shaft engaging the cylindrical wall within said groove and maintaining the flat surface of the shaft in operative association with the flat wall surface of the recess.

4. In a tool, a handle having a cylindrical shaped opening therein and a larger cylindrical shaped opening near the end of the handle, polygonal flat surfaces at the end of said second opening defining a recess of larger cross section than either of said cylindrical openings, a tool shaft having a cylindrical shaped end portion extending into the first opening in rotatable journalled relationship with the handle, a polygonal shaped portion of said tool shaft for being engaged by a wrench and of smaller cross sectional area than the second cylindrical opening, and a second polygonal shaped portion on said tool shaft adapted to engage the polygonal flat surfaces defining said recess for preventing rotation of the handle relative to the tool shaft.

5. In a tool, a handle having a cylindrical shaped opening therein and a larger cylindrical shaped opening near the end of the handle, polygonal flat surfaces at the end of said second opening defining a recess of larger cross section than either of said cylindrical openings, a tool shaft having a cylindrical shaped end portion extending into the first opening in rotatable journalled relationship with the handle, a polygonal shaped portion on said tool shaft for being engaged by a wrench and of smaller cross sectional area than the second cylindrical opening, a second polygonal shaped portion on said tool shaft adapted to engage the polygonal flat surfaces defining said recess for preventing rotation of the handle relative to the tool shaft, and releasable means retaining the tool shaft in a position with the second polygonal shaped portion out of engagement with the flat walls of said recess.

6. In a tool, a handle having a cylindrical shaped opening therein and a larger cylindrical shaped opening near the end of the handle, polygonal flat surfaces at the end of said second opening defining a recess of larger cross section than either of said cylindrical openings, a tool shaft having a cylindrical shaped end portion extending into the first opening in rotatable journalled relationship with the handle, a polygonal shaped portion on said tool shaft for being engaged by a wrench and of smaller cross sectional area than the second cylindrical opening,

a second polygonal shaped portion on said tool shaft adapted to engage the polygonal flat surfaces defining said recess for preventing rotation of the handle relative to the tool shaft, said cylindrical shaped opening having an annular groove therein, and a spring pressed ball carried by the cylindrical end portion of the tool shaft for engaging said annular groove.

7. In a screwdriver, a handle having a cylindrical shaped opening therein, a tool shaft having a cylindrical shaped end portion extending into said opening for journalled relation therein, an annular groove in the wall of said opening, a spring pressed ball carried by the periphery of the tool shaft engaging said annular groove and releasably retaining the tool shaft in a fixed position longitudinally of the handle, a lever arm receiving portion carried by said tool shaft adjacent the end of the handle, and a portion of larger cross sectional dimension than said lever arm receiving portion on said tool shaft.

8. In a manually operable tool, a handle having a cylindrical shaped opening therein and a larger cylindrical shaped opening at the end of the first opening and adjacent an end of the handle, said handle having a hexagonal shaped recess at the end of the second opening and terminating at the end of the handle defining a recess of larger cross section than the second cylindrical opening, a tool shaft having a cylindrical shaped end portion extending into the first opening in rotatable journalled relationship within the handle and slidable therein, a wrench engaging portion on said tool shaft substantially square in cross section and smaller in cross sectional dimensions than the diameter of the second cylindrical opening, an enlarged portion on the tool shaft hexagonal in cross section adapted to enter said recess for preventing rotation of the handle relative to the tool shaft, and releasable means within the first cylindrical opening retaining the tool shaft in position with the enlarged hexagonal portion thereon out of engagement with the hexagonal recess.

9. In a manually operable tool, a handle having a cylindrical shaped opening therein, a tool shaft having a cylindrical shaped end portion extending into said opening for journalled rotation therein and slidable axially of the handle, said opening having an annular groove therein, a spring-pressed member carried by the cylindrical shaped end portion of the tool shaft engaging said annular groove and releasably maintaining the tool shaft in a fixed position longitudinally of the handle, a wrench receiving portion carried by the tool shaft substantially square in cross section and extending into the opening in the handle, and a portion on the tool shaft of larger cross sectional dimension than said square portion defining the end of the square wrench receiving portion.
